UNITED STATES PATENT OFFICE.

OLIVER M. DE LAUNTY, OF CHICAGO, ILLINOIS, ASSIGNOR TO CHARLES H. JOY, OF CHICAGO, ILLINOIS.

GAS-ENGINE.

1,125,072.

Specification of Letters Patent.

Patented Jan. 19, 1915.

Application filed January 16, 1913. Serial No. 742,423.

To all whom it may concern:

- Be it known that I, OLIVER M. DE LAUNTY, a citizen of the United States, and resident of Chicago, county of Cook, and State of Illinois, have invented certain new and useful Improvements in Gas-Engines, of which the following is a specification, and which are illustrated in the accompanying drawings, forming a part thereof.
- 10 The invention relates to gas engines, and more particularly to those of that type having cylinders bored to two diameters and operated in pairs, the smaller bore of each cylinder being connected with the larger bore of the other cylinder and the latter serving as a pump chamber for receiving and compressing the explosive charge. Certain features of the invention, however, are applicable to gas engines generally, and the 20 object of the invention is to provide a gas engine which shall be efficient in operation and of improved form in structural detail.
- A feature of the invention provides an independent chamber intermediate the pump chamber and the power cylinder and serving to prevent the production of too great a pressure in the pump chamber, while still permitting such chamber to supply the explosive charge in the required quantity.
- 30 The invention is exemplified in the structure to be hereinafter described, and which is illustrated in the accompanying drawings, wherein—

Figure 1 is a side view of a gas engine embodying the features of improvement provided by the invention, some of the parts being shown in section and the planes of the section being indicated by the broken line 1—1 on Fig. 2; Fig. 2 is a plan sectional view of the engine taken on the broken line 2—2 of Fig. 1; Fig. 3 is a detail plan sectional view taken on the line 3—3 of Fig. 1; Figs. 4 and 5 are detail perspective views, partly in section, showing the construction 40 of a check valve used in the engine; and Figs. 6 and 7 are sectional views taken on the broken lines 6—6 and 7—7, respectively, of Fig. 2.

The engine illustrated in the drawings 50 comprises four cylinders. These are generally designated by the numerals 10, 11, 12 and 13. They are preferably surrounded by a common water jacket 14. As shown, the walls of all of the cylinders 10, 11, 12 and 13, and the side walls of the water

jacket 14 are cast integral in one piece. The water jacket 14 has an oblong rectangular opening 15 at its top, and a continuous outstanding foot flange 16.

The usual crank case 17 is provided below the cylinders. This crank case provides bearings 18, 19, for the crank shaft 20, and is made rigid with the walls of the several cylinders, as by being secured to the foot flange 16 by bolts 21. The top opening 15 of the water jacket 14 is normally covered by a removable top plate 22. The top plate 22 is formed with a nipple 23 adapted to serve as an outlet for water delivered to the chamber of the jacket 14. This water is preferably provided at the lower part of the chamber of the jacket, as through a duct 24 which leads through an opening in the end wall of the jacket.

A piston, as 25, 26, 27 and 28, operates in each of the cylinders 10, 11, 12 and 13. These pistons are connected by pitmen, as 29, to the several cranks 30, 31, 32 and 33 respectively of the crank shaft 20. Preferably the cranks of the crank shaft 20 are so arranged that the two pistons, as 25, 26, and 27, 28, of the pair of cylinders adjacent each end of the engine act in alternation, and that one piston of each of such pairs acts intermediate the two pistons of the other pair.

The corresponding cylinders of the two pairs and the pistons therefor are preferably of like construction. Each cylinder is shown as being bored upon two diameters whereby it is provided with an outwardly facing annular shoulder 34 intermediate its ends. When so constructed the part 35 of the cylinder above the shoulder serves as a power chamber and the part 36 of the cylinder below the shoulder serves as a pump chamber. The pistons 25, 26, 27 and 28 are each of a form complementary to that of the cylinder within which they respectively operate. Each piston accordingly has a smaller upper portion 37 and a larger base portion 38, the two portions 37 and 38 being located upon opposite sides of an annular shoulder 39.

The explosive charge is most desirably supplied downwardly through the cover plate 22 of the water jacket, as from a pair of nipples one of which is shown at 40. Each of these nipples leads from the usual manifold (not shown) and is secured to the cover plate 22 by bolts 41. Ducts, as 42 and 43,

43, lead downwardly within the chamber of the water jacket 14 from the nipple 40 to the pump chamber portions 36 of the two adjacent cylinders, as 10, 11 or 12, 13. Preferably each of these ducts leads into the corresponding pump chamber 36; through a port, as 44, located upon the annular shoulder 34 of the cylinder wall. Most desirably a downwardly opening check valve 45 is located in each of the ducts 42, 43. In order that this check valve may be adjacent the port 44 and still be readily movable at the top of the engine upon removal of the cover plate 22, it is carried by a sleeve 46 which fits within the duct. This sleeve rests upon an annular shoulder 47 formed in the wall of the duct, as 42 (Fig. 7). The cover plate 22 engages the higher end of the sleeve to prevent its displacement.

20 Transfer passages, as 48, 49, extend between the larger bore 36 of each cylinder and the smaller bore 35 of the other cylinder of the same pair. Most desirably these transfer passages, like the ducts 42, 43 are 25 cored into parts of the integral casting from which the cylinder walls and the side walls of the water jacket 14 are produced.

As shown, the port openings, as 50, 51, at the opposite ends of the ducts 48, 49, are 30 located upon the annular shoulder 34 of one cylinder and upon the side wall of the smaller portion 35 of the adjacent cylinder respectively. By this means the explosive charge drawn from the duct 42 or 43 upon 35 the downward movement of the piston is transferred to the smaller portion 35 of an adjacent cylinder upon the upward movement of the piston. To prevent too high a pressure being exerted at the port 51, an independent intermediate chamber communicating with each of the transfer passages, as 48, 49, is preferably provided. Two of these independent intermediate chambers are 40 shown in the drawing at 52 and 53. They are conveniently formed by coring out a 45 part of the common wall between the two adjacent cylinders, as 12, 13 above the transfer passages 48, 49, with which they respectively communicate.

50 A check valve, as 54, is preferably provided in each of the transfer passages 48, 49, below the corresponding intermediate chamber 52 or 53. As shown each of the check valves is constructed to be removed 55 through the top of the corresponding intermediate chamber 52, 53 when the cover plate 22 of the water jacket 14, has been removed. To this end, the top of each of the intermediate chambers 52, 53 is preferably closed 60 by a screw cap 55 (Fig. 6). The construction of each of the check valves 54, is more particularly illustrated in Figs. 4 and 5 of the drawings. It preferably comprises a cage having a cup shaped base portion 56, 65 and an open work cap 57. These parts are

removably connected as by a screw threaded engagement between the periphery of the cap 57 and the rim of the cup shaped base portion 56. The floor of the base portion 56 is provided with a plurality of apertures 58, each having flaring walls to provide a seat for a ball valve 59. The apertures 58 and the open work structure of the cap 57 permit the passage of gas upwardly through the valve. The ball valves 59 close the openings 58 against the downward movement of gas through the valve.

Each of the check valves 54 is preferably seated upon an upwardly facing annular shoulder 60, (Fig. 6) formed in the wall of the corresponding transfer passage 48, 49. To permit the valve to be conveniently lifted from its seat upon the removal of the top plate 22 and closure 55, the cap 57 is preferably provided with an upwardly extending central stem 61. The higher end of this stem is of reduced diameter and has sliding engagement with the closure plate 55. A spring 62 coiled about the upper end of the stem 61 and reacting between the under side 63 of the closure plate 55 and the annular shoulder 60 upon the stem, serves for yieldingly holding the check valve 54 against its seat upon the shoulder 60. Preferably the spring 62 will be of such strength as to prevent displacement of the casing of the check valve 54, except in the event of an explosion of gas in the corresponding pump chamber 36.

The several cylinders as 10, 11, 12 and 13 of the engine have exhaust ports, as 64, located upon the side walls of the cylinder in the manner usually employed in the case of two-cycle gas engines. Ducts, as 65, 66 and 67 communicate with the several exhaust ports 64 to deliver the products of combustion through the side wall of the water jacket 14. Preferably the walls of these ducts are formed integral with the walls of the cylinders and the side wall of the water jacket. The ducts 65 and 67 communicate with the exhaust port 64 of the cylinders 10 and 13, respectively. The duct 66 extends outwardly from between the cylinders 11 and 12 and communicates with the exhaust ports 64 of both of these cylinders.

By making the several parts of the engine in about the proportions shown in the drawings, the volume of each pump chamber 36 is greater than the volume of the combustion chamber 35 to which it delivers.

By forming the intake ports 44 and outlet ports 50 upon the annular shoulder 34 and by locating the check valves 45 and 54 adjacent these ports, respectively, a complete new charge of gas is drawn into each of the pump chambers 36 at each downward stroke of the corresponding piston and all of this gas is expelled from such pump chamber at the next up stroke of the piston. By these

means the explosive charges are introduced into the combustion chambers 35 at greater than atmospheric pressure.

The use of the intermediate chambers, as 52, 53, prevents a pressure of gas being exerted at the port openings 51 such as would cause leakage of gas between the adjacent side wall of the cylinder and the piston into the pump chamber 36 when the piston covers 10 the port opening. As the intermediate chambers 52, 53 are located within the chamber of the water jacket 14 and are thereby completely surrounded with hot water contained in this jacket, there will be no condensation of the vapors in these chambers such as usually occurs when a part of the explosive charge is temporarily retained in an intermediate chamber.

I claim as my invention-

20 1. In a gas engine, in combination, a pair of cylinders each having a bore of two diameters, pistons operating in said cylinders in alternation, each piston having an imperforate surface complementary in form to the bore of the corresponding cylinder, an induction port at the inner end of the larger bore of each cylinder, a pair of independent transfer passages extending between the cylinders, the port openings at the opposite 25 ends of each of said transfer passages being at the inner end of the larger bore of one cylinder and at the outer end of the smaller bore of the other cylinder, respectively, and a check valve in each of the said transfer 30 passages.

25 2. In a gas engine, in combination, a pair of cylinders each having a bore of two diameters, pistons operating in said cylinders in alternation, each piston having an imperforate surface complementary in form to the bore of the corresponding cylinder, an induction port at the inner end of the larger bore of each cylinder, a check valve controlling each of said induction ports, a pair of 35 independent transfer passages extending between the cylinders, the port openings at the opposite ends of each of said transfer passages being at the inner end of the larger bore of one cylinder and at the outer end of the smaller bore of the other cylinder, respectively, and a check valve in each of the said transfer 40 passages.

30 3. In a gas engine, in combination, a pair of cylinders, the bore of each cylinder having an outwardly facing annular shoulder intermediate its ends, pistons reciprocating in alternation one in each cylinder, each piston having an imperforate surface complementary in form to the bore of the corresponding cylinders, an induction port located upon the said annular shoulder of each cylinder, a check valve controlling the said induction port, a pair of independent transfer 45 passages extending between the cylinders, the port openings at the opposite ends

of each of said transfer passages being upon the said annular shoulder of one cylinder and at the outer end of the smaller bore of the other cylinder, respectively, and a check valve in each of the said transfer passages. 70

4. In a gas engine, in combination, a power cylinder, a water jacket surrounding the cylinder, a removable cover plate normally closing the top of the water jacket, an induction passage extending through the water jacket and its cover plate and opening at its lower end into the cylinder and having an instanding shoulder in its wall adjacent its lower end, a removable bushing fitting the said induction passage and extending between the said shoulder and the under side of the said cover plate, and a check valve mounted at the lower end of the said bushing and removable therewith upon the removal of the cover plate of the water 75 jacket. 80

5. In a gas engine, in combination, a pair of cylinders, the bore of each cylinder having an outwardly facing shoulder intermediate its ends, pistons reciprocating in alternation one in each cylinder, each piston having an imperforate surface complementary in form to the bore of the corresponding cylinder, the piston displacement in the larger bore of each cylinder being 85 greater than the piston displacement in the smaller bore of the other cylinder, an induction port located upon the said annular shoulder of each cylinder, a check valve controlling each of the said induction ports, a pair of transfer passages extending between the cylinders, the port openings at the opposite ends of each of said transfer passages being upon the said annular shoulder of one cylinder and at the outer end of the smaller bore of the other cylinder, respectively, and a check valve in each of the said transfer 90 passages. 95

6. In a gas engine, in combination, a combustion chamber, a compression chamber, an intermediate chamber communicating with both of the first mentioned chambers but having no other opening, a check valve between the compression chamber and the intermediate chamber, an explosive charge induction passage leading to the compression chamber and plungers working in the combustion chamber and compression chamber in alternation. 100

7. In a gas engine, in combination, a pair of combustion chambers, a pair of compression chambers, an independent intermediate chamber communicating with each of the compression chambers and one of the combustion chambers but having no other opening, a check valve located between each compression chamber and the corresponding intermediate chamber, an explosive charge induction passage leading to each compression chamber, and plungers working in the 105 110 115 120 125 130 135 140

- compression and combustion chambers of each pair in alternation.
8. In a gas engine, in combination, a combustion chamber, an intermediate chamber, a water jacket surrounding both of said chambers, a compression chamber, an induction passage leading through the water jacket to the compression chamber, a check valve between the compression chamber and the intermediate chamber, and plungers working in the combustion chamber and the compression chamber in alternation. 70
9. In a gas engine, in combination, a combustion chamber, an intermediate chamber, a water jacket surrounding both of said chambers, a compression chamber, an induction passage leading through the water jacket to the compression chamber, a check valve controlling the opening of the induction passage into the compression chamber, a check valve between the compression chamber and the intermediate chamber, and plungers working in the combustion chamber and the compression chamber in alternation. 75
10. In a gas engine, in combination, a pair of cylinders, the bore of each cylinder having an outwardly facing annular shoulder intermediate its ends, pistons reciprocating in alternation one in each cylinder, each piston having an imperforate surface complementary in form to the bore of the corresponding cylinder, an induction port located upon the said annular shoulder of each cylinder, a check valve controlling each of the said induction ports, a pair of transfer passages extending between the cylinders, the port openings at the opposite ends of each of said transfer passages being upon the said annular shoulder of one cylinder and at the outer end of the smaller bore of the other cylinder, respectively, a check valve in each of the transfer passages, and an independent intermediate chamber communicating with each of the transfer passages between the check valve and the port opening of such transfer passage into the smaller bore of the corresponding cylinder. 80
11. In a gas engine, in combination, a combustion chamber, a water jacket therefor, an intermediate chamber located within the chamber of the said water jacket, a compression chamber, an explosive charge induction passage leading to the compression chamber, a check valve between the compression chamber and the intermediate chamber and plungers working in the combustion chamber and the compression chamber in alternation. 85
12. In a gas engine, in combination, a combustion chamber, a water jacket therefor, an intermediate chamber located within the chamber of the said water jacket, a compression chamber, an explosive charge induction passage leading to the compression chamber, a check valve between the compression chamber and the intermediate chamber having a common wall with the said water jacket, a compression chamber, an explosive charge induction passage leading to the compression chamber, a check valve between the compression chamber and the intermediate chamber and plungers working in the combustion chamber and the compression chamber in alternation. 90
13. In a gas engine, in combination, a combustion chamber, a water jacket therefor, an intermediate chamber having a common wall with the said water jacket, a compression chamber, an explosive charge induction passage leading to the compression chamber, a check valve between the compression chamber and the intermediate chamber and plungers working in the combustion chamber and the compression chamber in alternation. 95
14. In a gas engine, in combination, a combustion chamber, a water jacket therefor, an intermediate chamber, a compression chamber, an explosive charge induction passage leading to the compression chamber, the said passage and the said intermediate chamber each having a common wall with the said water jacket, a check valve between the compression chamber and the intermediate chamber and plungers working in the combustion chamber and the compression chamber in alternation. 100
15. In a gas engine, in combination, a pair of cylinders each having a bore of two diameters, pistons operating in said cylinders in alternation, each piston having an imperforate surface complementary in form to the bore of the corresponding cylinder, an induction port at the inner end of the larger bore of each cylinder, a pair of independent intermediate chambers each having two port openings which are located, respectively, at the inner end of the larger bore of one cylinder and at the outer end of the smaller bore of the other cylinder, and a check valve controlling that one of the port openings of each of the said intermediate chambers which is located at the inner end of the larger bore of a cylinder. 105
16. In a gas engine, in combination, a pair of cylinders each having a bore of two diameters, pistons operating in said cylinders in alternation, each piston having an imperforate surface complementary in form to the bore of the corresponding cylinder, an induction port at the inner end of the larger bore of each cylinder, a check valve controlling each of said induction ports, a pair of independent intermediate chambers each having two port openings which are located, respectively, at the inner end of the larger bore of one cylinder and at the outer end of the smaller bore of the other cylinder, and a check valve controlling that one of the port openings of each of the said intermediate chambers which is located at the inner end of the larger bore of a cylinder. 110
17. In a gas engine, in combination, a pair of cylinders each having a bore of two diameters, pistons operating in said cylinders in alternation, each piston having an imperforate surface complementary in form to the bore of the corresponding cylinder, an induction port at the inner end of the larger bore of each cylinder, a check valve controlling each of said induction ports, a pair of independent intermediate chambers each having two port openings which are located, respectively, at the inner end of the larger bore of one cylinder and at the outer end of the smaller bore of the other cylinder, and a check valve controlling that one of the port openings of each of the said intermediate chambers which is located at the inner end of the larger bore of a cylinder. 115
18. In a gas engine, in combination, a pair of cylinders each having a bore of two diameters, pistons operating in said cylinders in alternation, each piston having an imperforate surface complementary in form to the bore of the corresponding cylinder, an induction port at the inner end of the larger bore of each cylinder, a check valve controlling each of said induction ports, a pair of independent intermediate chambers each having two port openings which are located, respectively, at the inner end of the larger bore of one cylinder and at the outer end of the smaller bore of the other cylinder, and a check valve controlling that one of the port openings of each of the said intermediate chambers which is located at the inner end of the larger bore of a cylinder. 120
19. In a gas engine, in combination, a pair of cylinders each having a bore of two diameters, pistons operating in said cylinders in alternation, each piston having an imperforate surface complementary in form to the bore of the corresponding cylinder, an induction port at the inner end of the larger bore of each cylinder, a check valve controlling each of said induction ports, a pair of independent intermediate chambers each having two port openings which are located, respectively, at the inner end of the larger bore of one cylinder and at the outer end of the smaller bore of the other cylinder, and a check valve controlling that one of the port openings of each of the said intermediate chambers which is located at the inner end of the larger bore of a cylinder. 125
20. In a gas engine, in combination, a pair of cylinders each having a bore of two diameters, pistons operating in said cylinders in alternation, each piston having an imperforate surface complementary in form to the bore of the corresponding cylinder, an induction port at the inner end of the larger bore of each cylinder, a check valve controlling each of said induction ports, a pair of independent intermediate chambers each having two port openings which are located, respectively, at the inner end of the larger bore of one cylinder and at the outer end of the smaller bore of the other cylinder, and a check valve controlling that one of the port openings of each of the said intermediate chambers which is located at the inner end of the larger bore of a cylinder. 130

- of cylinders, the bore of each cylinder having an outwardly facing annular shoulder intermediate its ends, pistons reciprocating in alternation one in each cylinder, each 5 piston having an imperforate surface complementary in form to the bore of the corresponding cylinder, an induction port located upon the said annular shoulder of each cylinder, a check valve controlling the said induction port, and a pair of independent intermediate chambers each having two port openings, which are located, respectively, upon the said annular shoulder of one cylinder and at the outer end of the smaller bore 10 of the other cylinder, and a check valve controlling that one of the port openings of each of the said intermediate chambers which is located upon the said annular shoulder of a cylinder.
- 15 20. 18. In a gas engine, in combination, a power cylinder, a pumping cylinder, a chambered casing, passages connecting the chamber of the casing with both of said cylinders, a water jacket surrounding the power cylinder and casing, a removable cover plate normally closing the top of the water jacket, a cap detachably fitting the top of the said casing below the said cover plate and normally closing the chamber of the casing and a check valve controlling the passage between the chamber of the casing and the pumping cylinder, said check valve being removable through the top of the casing and water jacket upon removal of the 25 said cover plate and cap.
- 30 35. 19. In a gas engine, in combination, a pair of upright cylinders each having a bore of two diameters, pistons operating in said cylinders in alternation, each piston being complementary in form to the bore of the corresponding cylinder, a pair of upright tubular casings located between the cylinders, a port connecting the larger bore 40
- of each cylinder with the bore of one of said tubular casings at its foot, a valve controlling each of said ports, a port connecting the bore of each casing above the corresponding one of the said valves with the smaller bore of the cylinder other than the one having its larger bore connected with the bore of the same casing by one of the first named ports, and a cap removably fitting the top of each casing, each of the said valves being removable through the top of the corresponding casing upon removal of the 45 50 55 corresponding cap.
20. In a gas engine, in combination, a pair of upright cylinders each having a bore of two diameters, pistons operating in said cylinders in alternation, each piston being complementary in form to the bore of the corresponding cylinder, a pair of upright tubular casings located between the cylinders, a port connecting the larger bore of each cylinder with the bore of one of said tubular casings at its foot, a valve controlling each of said ports, a port connecting the bore of each casing above the corresponding one of the said valves with the smaller bore of the cylinder other than the one having its larger bore connected with the bore of the same casing by one of the first named ports, a water jacket surrounding the said cylinders and casings, a removable cover plate normally closing the top of the water jacket, and a cap detachably fitting the top of each of the said casings below the said cover plate, each of the said valves being removable through the top of the corresponding casing and top of the water jacket upon removal of the said cover plate and corresponding cap.
